WELL REAMER

Frank Ellingsen, Brea, Calif., assignor to Chik-san Oil Tool Company, Ltd., Fullerton, Calif., a corporation of California

Application May 6, 1936, Serial No. 78,163

14 Claims. (Cl. 255—73)

This invention relates to a well drilling tool and relates more particularly to a well reamer. A general object of this invention is to provide a simple, practical and particularly effective well reamer.

Well reamers employed in the rotary method of well drilling usually embody cutters rotatable about substantially vertical axes and provided with teeth for engaging the formation at the side wall of the well bore. It is the common practice to make the teeth of reamer cutters axial or in axial planes. It has been found that such axial teeth track or follow one another in their engagement with the earth formation making vertical grooves in the wall of the well, and, therefore, are not efficient in cutting away the formation or in smoothing the wall of the well.

Another object of this invention is to provide a reamer having cutters whose teeth do not track in their engagement with the wall of the well or form grooves in the wall of the well.

Another object of this invention is to provide a well reamer embodying cutters that are very rapid and efficient in their cutting action and in providing the well with a smooth even side wall.

Another object of this invention is to provide cutters for a well reamer that are effective in their reaming engagement with the wall of the well having cutting parts or teeth formed and related to properly ream the well without tracking or forming grooves.

Another object of this invention is to provide cutters for a well reamer provided with cutting parts which are zigzag or made up of portions which are alternately spiralled or pitched in opposite directions whereby they are particularly efficient as they cannot groove or track in their action on the formation during rotation and downward feeding of the reamer.

Another object of this invention is to provide reamer cutters of the character mentioned that are very simple and inexpensive of manufacture.

Another object of this invention is to provide a well reamer provided with circumferentially spaced rotatable cutters having series of teeth with portions alternately pitched or spiralled in opposite directions, the teeth of the several cutters being related so that their spiralled portions in common or corresponding horizontal planes are pitched in different directions to be particularly efficient in their cutting action.

A further object of this invention is to provide an improved well reamer of the character mentioned that is simple and sturdy in construction.

The various objects and features of my inven-

tion will be fully understood from the following detailed description of typical preferred forms and applications of the invention, throughout which description reference is made to the accompanying drawings, in which:

Fig. 1 is a side elevation of one form of the present invention. Fig. 2 is an enlarged fragmentary vertical detailed sectional view of the reamer being a view taken substantially as indicated by line 2—2 on Fig. 1. Figs. 3, 4, and 5 are enlarged transverse detailed sectional views taken substantially as indicated by lines 3—3, 4—4, and 5—5, respectively, on Fig. 1. Fig. 6 is a fragmentary side elevation of a modified form of the invention and Fig. 7 is a fragmentary side elevation of an alternative form of cutter.

The well reamer of the present invention illustrated in Figs. 1 to 5, inclusive, of the drawings, includes, generally, a shank or body 10, shafts or pins 11 removably carried by the body 10 and cutters 12 rotatable on the pins 11.

The shank or body 10 is adapted to be connected or interposed in a drilling string for operation in a well. The body 10 is an elongate member whose upper and lower end portions may be cylindrical. Means are provided at the opposite ends of the body 10 for facilitating its connection in a drilling string. In the particular case illustrated in the drawings a screw threaded pin 13 is provided on one end of the body and a tapered screw threaded socket 14 is provided in the other end of the body for cooperating with spaced connecting parts of the string. The main or intermediate portion 15 of the body 10 is shaped to carry the pins 11 and the cutters 12. In the typical form of the invention illustrated the body portion 15 is substantially triangular in horizontal cross section to carry three pins 11 and three reamer cutters 12.

The upper and lower ends 16 of the triangular portion 15 are preferably bevelled or inclined. Vertical or longitudinal recesses 17 are provided in the apex parts of the body portion 15 to receive the cutters 12. The recesses 17 have suitably concaved inner walls 18. The upper and lower walls 19 of the recesses 17 may be flat and horizontal. Axial or vertical openings 20 extend through the body portion 15 from the lower ends of the recesses 17 to its lower end 16. Vertical openings 21 are provided in the body portion 15 and extend from the upper ends of the recesses 17 to the upper end of the portion 16. The openings 20 and 21 communicating with a recess 17 are longitudinally aligned and are polygonal in cross section. The openings 21 are preferably

larger in diameter than the openings 20. The openings 20 and 21 may be provided by milling or otherwise forming flat sided grooves in the body portion 15 from its outer surfaces and then 5 closing the outer sides of the grooves thus formed with welded on plates or inserts 22. The outer sides of the inserts 22 are preferably flush with the surfaces of the body portion 15. The shank or body 10 of the reamer is provided with a 10 central longitudinal fluid passage 23 extending through it from one end to the other.

The pins 11 are removably carried by the body 10 to support the cutters 12 for rotation in the body recesses 17. The pins 11 are simple 15 elongate members whose opposite end portions are supported in the openings 20 and 21. Each pin 11 has a polygonal end portion 24 fitting an opening 20, a cylindrical portion 25 extending through a recess 17 and a polygonal end portion 20 26 fitting an opening 21. An axially facing shoulder 27 occurs between the portions 24 and 25 of each pin 11 to bear against the lower wall 19 of a groove 17. The cooperation of the polygonal or flat sided pin portions 24 and 26 with the 25 walls of the polygonal openings 20 and 21 effectively holds the pins against rotation. In assembling the reamer, the pins 11 are introduced through the openings 21 and are passed through the recesses 17 to have their polygonal portions 30 24 enter the openings 20.

Simple dependable means are provided for removably locking or retaining the pins 11 in position on the body 10. Transverse or horizontal openings 28 are provided in the body portion 15 35 to intersect the openings 21. The polygonal portions 26 of the pins 11 have transverse openings 29 registering with the openings 28. Bolts 30 are passed through the openings 28 and 29 to hold the pins 11 against longitudinal movement 40 and dependably attach them to the body 10. Nuts 31 are threaded on the bolts 30 and the heads of the bolts and the nuts 31 are countersunk in suitable counter bores at the opposite ends of the openings 28.

45 The cutters 12 are important features of the present invention. The cutters 12 are elongate members and are cylindrical in their general configuration. The reamer cutters 12 are rotatable on the pins 11 having central longitudinal openings 32 rotatably receiving the cylindrical portions 25 of the pins 11. The opposite ends of the cutters 11 are preferably flat and thrust washers 33 are provided on the pins 11 between the ends of the cutters and the end walls 19 of 50 the recesses 17. The cutters 12 rotatably supported on the pins 11, as just described, are adapted to rotate about substantially vertical axes and project outwardly from the recesses 17 to act on the side wall of the well bore as the 55 reamer is rotated and fed downwardly in the usual manner. In the preferred construction the opposite end portions of the cutters 11 are bevelled or tapered as illustrated throughout the drawings.

60 The cutters 12 are provided with peripheral teeth or cutting parts 34 which are formed and disposed to be particularly efficient in their cutting action. The cutting parts 34 extend axially or longitudinally of the cutters 12 and in the 65 small size and medium size cutters may be continuous, extending throughout the length of the cutters. The teeth or cutting parts 34 are relatively sharp being substantially V-shaped in horizontal cross section to have sharp outer cutting 70 edges 35. The cutting parts 34 are separated

by grooves 36 which may have substantially flat bottoms. The opposite end portions 37 of the cutting parts 34 occurring on the tapered end portions of the cutters may be straight and in vertical planes. 5

The shape or longitudinal disposition of the major portions of the cutting parts 34 is important as it insures the rapid efficient cutting action of the cutters. In accordance with the invention the teeth or cutting parts 34 are zigzag 10 in shape having alternate portions spiralled or pitched in opposite directions. In accordance with the broader aspects of the invention the cutting parts 34 may have any desired or suitable number of oppositely inclined or spiralled portions. 15 In the form of cutter 12 illustrated in Figs. 1 and 2 of the drawings the cutting parts 34 each have three spiralled or inclined portions; namely, two portions A spiralled or inclined in the same direction and a middle or intermediate portion B inclined in the opposite direction. The corresponding inclined portions A and B of the several cutting parts 34 of a cutter are preferably substantially parallel. The endmost inclined portions A of the cutting parts 34 are illustrated as 20 inclined or spiralled downwardly and rearwardly relative to the direction of rotation of the cutters 12 about their individual axes while the intermediate inclined portions B are inclined downwardly and forwardly relative to the direction of rotation of the cutters about their individual axes, it being understood that this relationship of the inclined or spiralled portions A and B of the cutting 25 parts 34 may be substantially equal in length, it being apparent that the length of the inclined portions may be varied if desired.

In the manufacture of the cutters 12 it has been found practical to translate a milling cutter longitudinally of a cutter 12 while alternately oscillating or partially turning the cutter 12 in opposite directions. Thus the milling cutter operates to form the spiralled zigzag grooves 36 leaving the cutting parts 34, it being understood 40 that the movements of the cutter 12 and the milling cutter are related to provide cutting parts 34 of the desired configuration. When forming 45 the teeth or cutting parts on large cutters in this manner the cutting parts are rather broad or 50 blunt at the points where their oppositely inclined portions join. If such broad or blunt parts are present spaced annular grooves 38 may be cut in the periphery of the cutter to provide 55 one or more spaced relatively sharp teeth 39 at or adjacent the points of joinder of the oppositely inclined portions of the cutting parts. Fig. 7 of the drawings illustrates such annular grooves 38 in a cutter 12 providing or leaving spaced teeth 39. The cutter illustrated in Fig. 7 of the drawings may be in all other respects similar to the cutters 12 described above, or the cutter illustrated in Fig. 6.

Fig. 6 of the drawings illustrates a form of the invention involving cutters 12^a having zigzag 65 teeth or cutting parts 40 having an even number of inclined or spiralled portions. The cutting parts 40 may be of the same transverse configuration as the cutting parts 34 and may be formed in the same manner as the cutting parts 70 34. In the particular case illustrated the teeth or cutting parts 40 of each cutter 12^a have four inclined portions with the alternate inclined portions spiralled or pitched in opposite directions. The end portions 41 of each cutting part 40 on 75

the tapered end portions of the cutters 12^a may be straight and in vertical planes. The principal part of each tooth or cutting part 40 has four alternately inclined portions C, D, E, and F. 5 Where there is an even number of alternate spiraled portions on the cutting parts 40 it will be noted that the endmost inclined portions C and F of a cutter 12^a are inclined in opposite directions. Where this relationship exists it may be 10 preferred to relate the cutters 12^a so that one cutter 12^a is positioned with the inclined or spiraled portions C adjacent its upper end and an adjacent cutter 12^a has its spiraled tooth portions F adjacent its upper end. In other words 15 it may be desired to relate the cutters 12^a of the reamer so that their spiraled cutting teeth portions in the same or corresponding horizontal zones are inclined or pitched in opposite directions. It is to be noted that the several cutters 20 12^a of the reamer illustrated in Fig. 6 of the drawings may be identical in construction and the relationship just described may be brought about by arranging the cutters in inverted or reversed position. Fig. 6 of the drawings illustrates the relationship just described, it being noted that the horizontally aligned spiraled portions of the cutting parts 40 of the two cutters 12^a are pitched in opposite directions. The 25 cutters 12^a formed and related as illustrated in Fig. 6 of the drawings are particularly efficient as there is no possibility of their cutting parts 40 tracking or following one another in their action on the earth formation.

In the operation of the form of the invention 30 illustrated in Figs. 1 to 5, inclusive, of the drawings the body 10 is connected in a drilling string to be operated in a well in the usual manner. As the drilling string is rotated the cutters 12 have active or cutting engagement with the side wall 40 of the well bore. The teeth or cutting parts 34 cut into the earth formation to ream and smooth the wall of the well. Due to the pitch or inclination of the portions A and B of the teeth 34 the teeth do not track in their action on the formation 45 as the reamer is rotated and fed downwardly. The cutting parts 34 having alternately inclined spiraled portions operate to shear or cut away the formation as they rotate about their individual axes while the reamer rotates and moves downwardly. The cutters 12 having cutting parts 34 with portions alternately inclined in opposite directions are particularly rapid and efficient in their reaming action and insure the balanced even operation of the reamer. The 50 cutters illustrated in Figs. 6 and 7 of the drawings operate in substantially the same manner as the cutters 12. The cutters of the present invention are simple and easy to manufacture and are dependably mounted or supported on the body of the tool. The pins 11 may be readily removed 55 from the body to permit the replacement of the cutters.

Having described only typical preferred forms and applications of my invention I do not wish 60 to be limited or restricted to the specific details herein set forth, but wish to reserve to myself any variations or modifications that may appear to those skilled in the art or fall within the scope of the following claims:

70 Having described my invention, I claim:

1. A cutter for a well reamer comprising a body adapted for rotation as a unit about its longitudinal axis, and a longitudinally extending cutting tooth on the body having portions pitched in opposite directions, said tooth portions extend-

ing in a direction generally axial of the body and being shorter than the circumference of the body.

2. A cutter for a well reamer comprising a body to be supported for rotation as a unit, and an axially extending cutting tooth on the body having portions pitched relative to the plane of the axis of rotation of the body, said portions being pitched in opposite directions, and having lengths less than the circumference of the body. 10

3. A cutter for a well reamer comprising a single body to be supported for independent rotation, and a plurality of circumferentially spaced cutting parts extending longitudinally on the body and having portions spiraled in opposite directions. 15

4. A cutter for a well reamer comprising a body to be supported for independent rotation as a unit, and a plurality of spaced axially extending cutting parts on the body extending between the opposite end parts of the body and having alternate portions spiraled in opposite directions. 20

5. A cutter for a well reamer comprising a body to be supported for independent rotation as one member, and a plurality of spaced substantially parallel axially extending cutting parts on the body having an even number greater than two of alternate portions pitched in opposite directions. 25

6. In a well reamer, a support, and a cutter 30 comprising a body arranged for independent rotation on the support as a unit, and a series of circumferentially spaced cutting parts extending longitudinally on the body and having portions pitched in opposite directions. 35

7. In a well reamer, a support, and a cutter comprising a body arranged for independent rotation on the support as a unit, and circumferentially spaced axially extending cutting teeth 40 projecting from the body and having portions pitched in opposite directions.

8. In a well reamer, a substantially vertical support, and a cutter comprising a body rotatable on the support as a unit, and a plurality of circumferentially spaced axially extending teeth on the body having portions pitched in opposite directions, said teeth being substantially parallel. 45

9. In a well reamer, a support, and a cutter comprising a body rotatable on the support as a single element, a multiplicity of circumferentially spaced axially extending cutting parts on the body having separated portions spiraled in opposite directions, and teeth between the separated portions of the cutting parts. 50

10. A well reamer including a body, a support 55 on the body, and a cutter comprising a body rotatable on the support as a unit, and a plurality of circumferentially spaced cutting parts on the cutter body adapted to project from the reamer body to contact the wall of the well and each having portions spiraled in opposite directions. 60

11. A well reamer including a body having a recess, and polygonal openings communicating with the opposite ends of the recess, a removable pin having polygonal end portions fitting said openings, the pin passing through the recess, a cutter rotatable on the pin, and removable means holding the pin against longitudinal displacement. 70

12. A well reamer including a body, a plurality of circumferentially spaced supports on the body, pins carried by the supports, and a cutter rotatable on each pin as a complete cutting unit, the cutters each including a series of circumferen- 75

tially spaced cutting parts having portions spiralled in opposite directions.

13. A well reamer including a body, a plurality of circumferentially spaced pairs of vertically spaced supports on the body, a pin extending between and carried by the supports of each of said pairs, and a cutter rotatable as a unit on each pin, the cutters each including a series of circumferentially spaced axially extending cutting parts each having alternate portions spiralled in opposite directions.

14. A well reamer including a body, a plurality

of circumferentially spaced pairs of vertically spaced supports on the body, a pin extending between and carried by the supports of each of said pairs, and a cutter rotatable as a single member on each pin, the cutters each including a series of circumferentially spaced axially extending cutting parts each having alternate portions spiralled in opposite directions, the spiralled portions of the cutting parts of the cutters lying in common horizontal zones being pitched in opposite directions. 5 10

FRANK ELLINGSEN.
